UNITED STATES PATENT OFFICE.

HENRY C. THOMSON, OF BOSTON, MASSACHUSETTS, ASSIGNOR TO ELECTRIC GOODS MANUFACTURING COMPANY, OF BOSTON, MASSACHUSETTS, A CORPORATION OF MAINE.

INTERCOMMUNICATING TELEPHONES.

No. 898,820.

Specification of Letters Patent. Patented July 21, 1908.

Application filed March 20, 1907. Serial No. 363,333.

To all whom it may concern:

Be it known that I, HENRY C. THOMSON, a citizen of the United States, residing at Boston, in the county of Suffolk and State of Massachusetts, (whose post-office address is 115 Purchase street, Boston, Massachusetts,) have invented new and useful Improvements in Intercommunicating Telephones, of which the following is a specification.

The invention relates to intercommunicating telephones and has for its primary object the elimination of the disadvantages and objections incident to the use of a "junction box" such as is commonly employed in this class of telephones in making the connections from the instrumentalities carried by the telephone box or casing of each station with the main conductor wires which connect the different stations.

As is well known the junction box is usually, if not always located at or near the ceiling of the room, in which the telephone is located or in some out-of-the-way place where it is not conveniently accessible. Branch wires lead from the backboard of the telephone casing or box to the junction box where each branch wire is connected with the proper main conductor wire of the cable which leads from junction box to junction box. This manner of connecting the various instrumentalities within the telephone casing or box with the main cable wires by means of a junction box introduced into the main cable is cumbersome and expensive in the first instance, is liable to result in erroneous connections at the junction box unless great care is exercised in making such connections and causes delays and inconvenience in correcting any errors or in making tests to locate any defects in the system. These objectionable features are eliminated in practicing the present invention by leading the main cable wires which run from station to station directly to the backboard of the telephone casing or box of each station and there making connections directly with the wires from the various instrumentalities in the box or casing.

With this construction and arrangement the cumbersome and expensive junction box is eliminated and the connections with the main conductor wires are made where they are conveniently accessible both for install-

ing the apparatus and for making any corrections or tests. This construction also enables the backboard to be put in place during the construction of a building and the main conductor wires to be attached thereto, the box or part of the casing carrying the switch or other mechanisms for that station being secured to the backboard after the interior finish of the room is completed and the proper connections between these instrumentalities and the main conductor wires being readily and conveniently made.

In order that the connections between the station instrumentalities and the main line wires may be readily made, I provide the backboard of the telephone casing with a series of metal plates corresponding to the number of main conductor wires in the line cables and provide each plate with three binding screws, one for attaching the end of the incoming main conductor wire, one for attaching the end of the corresponding outgoing main conductor wire, and the third for connecting the wire leading to the proper part of the apparatus carried by the telephone casing or box, of which the backboard forms a part.

Any form of switching and calling mechanism may be employed in practicing the invention and one suitable form of such mechanism is shown in the drawings which I have prepared to illustrate a concrete embodiment of the invention.

In these drawings Figure 1 shows two stations of an intercommunicating telephone system provided with the present invention. Fig. 2 is a view showing the backboard of one of the telephone boxes or casings and also showing the mechanism carried by said casing. Fig. 3 is an enlarged elevation showing one of the plates on the backboard; and Fig. 4 is a sectional view showing the same.

As shown in the drawings the cables 1 which contain the main conductor wires connecting the various stations of the system, lead directly to and from the backboards of the telephone boxes or casings 2 for the different stations.

The backboard 3 of each telephone box is provided with a series of metal plates 4 corresponding in number to the number of main conductor wires in the cables 1. The end of each wire of the incoming cable 1 is connected by means of a screw 5 with one of the

plates 4 and the end of the corresponding wire in the outgoing cable 1 is connected to the same plate by means of a binding screw 6. For instance the main conductor wires of 5 the ringing battery circuit are connected to the plate 4 indicated at R. B., the main conductor wires of the talking battery circuit are connected to the plate indicated at T. B., the main conductor wires for the home station (the station indicated in Fig. 2) are connected to the plate H., the main conductor wires for the common return circuit are connected to the plate C. R., and the main conductor wires for the different stations in the 10 system are connected to the plates marked #1 to #8, the telephone mechanism being intended for use in a system having nine inter-communicating stations.

Each plate 4 is provided with a third binding screw 7 by which a clip 8 is secured to the plate 4. Each clip 8 is connected with a wire 9 leading to the proper part of the switch or other mechanism carried in the box 4^a which is hinged to the back plate 3.

25 By means of the plates and binding screws on the backboard 3 the wires 9 leading from the various instrumentalities carried by the box 4^a are directly connected with the main conductor wires contained within the incoming and outgoing cables 1. With this construction the main conductor wires which lead from station to station are connected directly to the backboard of each station so that the connection between the wires 9 and 30 these main conductor wires may be readily and accurately made and any changes in the connections may be readily effected to correct any errors. The main conductor wires

may also be exposed by opening the box 4^a so that any tests for imperfections or defects 40 along the line may be readily made. With this construction also the proper connections between the main conductor wires and the backboard may be made during the construction of a building and the connection 45 between the wires 9 and these main conductor wires be made after the interior finish of the room in which the telephone box is located has been completed.

Without attempting to point out the various forms of mechanism which may be employed in practicing the invention, what I desire to claim is:—

An intercommunicating telephone apparatus comprising a series of telephone boxes or 55 casings, each containing switching and calling mechanism, a main conductor cable leading directly from box to box and containing station wires equal in number to the number 60 of stations, common return talking and ringing battery wires, metallic plates on the back-board of each box corresponding in number to the number of main conductor wires in the main cable, means for connecting the incoming and outgoing main cable 65 wires to the respective plates and wires connecting the respective plates with the switching and calling mechanism, substantially as described.

In witness whereof, I have hereunto signed 70 my name this fifteenth day of March, 1907, in presence of two witnesses.

HENRY C. THOMSON.
